US0D1087371S

(12) **United States Design Patent** (10) Patent No.: **US D1,087,371 S**
(45) Date of Patent: ** Aug. 5, 2025

(54) **MASK**

(71) Applicant: **Therabody, Inc.**, Los Angeles, CA

(US)

(72) Inventors: **Benjamin Nazarian**, Beverly Hills, CA (US); **Jaime Sanchez Solana**, Los Angeles, CA (US); **Eduardo Merino**, Los Angeles, CA (US); **Mandar Deshmukh**, Los Angeles, CA (US); **Kevin Xie**, Los Angeles, CA (US); **William Webb**, San Francisco, CA (US)

(73) Assignee: **Therabody, Inc.**, Los Angeles, CA (US)

(**) Term: **15 Years**

(21) Appl. No.: **29/957,385**

(22) Filed: **Aug. 13, 2024**

Related U.S. Application Data

(63) Continuation of application No. 29/913,374, filed on Sep. 29, 2023, now Pat. No. Des. 1,039,710, which is (Continued)

(57) **CLAIM**

The ornamental design for a mask as shown and described.

DESCRIPTION

FIG. 1 is a top front isometric view of a mask showing the claimed design;

FIG. 2 is a top rear isometric view thereof;

FIG. 3 is a bottom rear isometric view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a top plan view thereof; and,

FIG. 9 is a bottom plan view thereof.

The broken lines in the figures show portions of the mask that form no part of the claimed design.

1 Claim, 9 Drawing Sheets

Related U.S. Application Data

a continuation of application No. 29/875,687, filed on May 9, 2023, now Pat. No. Des. 1,004,791, which is a continuation of application No. 29/868,829, filed on Dec. 14, 2022, now Pat. No. Des. 995,805.
